FLUID PASSAGE FOR DRILLING TOOLS

John A. Zublin, Los Angeles, Calif.

Application June 2, 1936, Serial No. 83,079

4 Claims. (Cl. 255—61)

The present invention relates generally to tools for drilling wells, and is particularly concerned with means for conducting and directing to the bottom of the hole the circulation fluid used to clean the cutting elements and carry cuttings to the surface.

In drilling tools of various types, the circulation fluid is often discharged from the tool at a point considerably above the bottom of the hole. As a result, the cutting elements are sometimes not cleaned as effectively as they should be, and the stream of fluid does not clear away all the cuttings, but instead leaves a layer of them over the bottom. To operate with best efficiency, the stream of fluid should be led as near to the bottom of the hole as possible and in such a way that it washes the sides of the bore and flushes all cuttings off the bottom. As the fluid passes the cutting elements, they will be washed clean.

Thus it is a general object of my invention to improve fluid circulation by providing a drilling tool with fluid passages that conduct the circulation fluid to a point very near the bottom of the well to wash away all cuttings and clean the cutting elements of the tool.

It is also an object to provide a drilling tool with fluid passages such that the fluid washes the sides of the hole as well as the bottom.

To achieve these objects in a drilling tool having an internal passage for circulation fluid, I provide an external channel which receives fluid from the internal passage and which extends down an outer face of the tool to a point near the bottom of the tool. The channel is open on one side, and is so positioned on the tool that it is very close to the vertical wall of the well. The well wall acts as a closure for the open side of the channel and fluid is, with the cooperation of the well wall, at least partially confined in the channel.

How these and other objects and advantages of the invention are attained will best be understood from reference to the following description and the annexed drawing, in which:

Fig. 1 is a side elevation of a drill bit with cone cutters, the body of the bit being broken away to show the external water channel;

Fig. 2 is an elevation of another type of bit with movable cutters showing the external water channel in elevation;

Fig. 3 is a fragmentary elevation partially broken away to show external water channels in a core head having fixed cutting blades;

Fig. 4 is a horizontal section on line 4—4 of Fig. 3; and

Fig. 5 is an elevation of a 4-way drag bit with external water channels.

There is shown in Fig. 1 a conventional type of drilling bit having a body or shank 10 provided at its upper end with a threaded pin 11 by means of which the bit is attached to a string of drill pipe for rotation. The cutting elements are the cone cutters 12 rotatably mounted in any suitable manner upon the lower portion of body 10. Body 10 is provided with an internal passage 15 which receives from the drill pipe the circulation fluid used to keep the cutting elements clean and carry cuttings to the surface.

The tool is provided with one or more external fluid channels 18 which communicate at their upper ends with internal passage 15, each channel receiving circulation fluid through a nozzle 19. Each channel 18 is preferably generally U-shaped in cross-section, although it will be realized that the exact shape and relative dimensions may be varied considerably, and so is open to the tool exterior along one side as well as at its lower end. The channel 18 is so positioned on the tool that it is in close proximity to the vertical wall 20 of the well; that is, it is placed so that the portions of the tool at the sides of the channel have but a small clearance between them and the sides of the well. In this way, wall 20 acts as a closure member that at least partially, though usually not completely, closes the open side of the U-shaped channel 18 to confine the stream of fluid therein. Of course, the clearance between the tool and wall 20 will permit a certain proportion of the circulation fluid to move outwardly, but the clearance is small and the partial closure of the channel is sufficient to maintain in each channel a definite downward flow of fluid confined therein and issuing for the most part at the bottom of the channel.

With this construction, the stream of circulation fluid issuing from nozzle 19 strikes wall 20 and is deflected downwardly in a stream that, with the cooperation of the well wall, is confined and conducted downwardly by channel 18 to a point near the bottom of the tool where it is discharged at the bottom of the well. It will be understood that the stream of fluid washes down the sides of the wall before it reaches the bottom of the well where it flushes the cutters and carries away debris, and that as the bit rotates in the well, each channel 18 passes in front of the entire circumference of wall 20 so all portions

of wall 20 at some time act to confine the fluid stream.

Fig. 2 shows the application of the invention to another type of drilling tool fully described and claimed in my copending application Ser. No. 71,600, filed March 30, 1936, on "Rotary drill bit with rolling cutters". The bit has a body 25 upon which are rotatably mounted a pair of carriers 26, each provided about its periphery with a number of cutters 27. As before, channel 18a is placed in the body of the tool where it will be in close proximity to the walls of the well. The channel receives circulation fluid at its upper end from the internal fluid passage 15 through nozzle 29.

Where the tool has fixed cutting elements as, for example, blades, the external channel may be placed in these blades instead of the body of the tool as described above, in order to bring it into proper position to cooperate with the well wall. A construction of this type is shown in Figs. 3 and 4, wherein is illustrated the lower end of a core bit comprising a head 30 attached to the lower end of the outer barrel 31, and an inner barrel 32 for receiving the core. Core head 30 is here illustrated as having four cutting blades 34, although a larger or smaller number may be used. Circulation fluid flows downwardly through the annular space 36 between the inner and outer barrels and thence through passages 37 to the upper ends of external channels 18b which are placed one each in the outer faces of blades 34.

Since the vertical edges of blades 34 are used for reaming, the forward edges of these blades will contact wall 20 of the hole being drilled, while the rear edge will clear the wall slightly, as shown in Fig. 4; though after the bit has been worn, both the forward and rear edges of the blade may touch the hole sides, thus completely closing the open side of channel 18b. In the same manner as described before, a stream of circulation fluid will enter the upper end of each external channel 18b from passage 37 and move downwardly therein. Since it is confined within the channel by wall 20, which covers the open vertical side of the channel, the stream then issues from the channel at a point near the bottom of the tool. The fluid moving downwardly through the channel washes the walls 20 and, as the bit rotates, 50 comes in contact with all portions of the wall.

Fig. 5 illustrates a four-blade drag bit having external water channels 18c down the outer edges of the blades 40, in the same manner as those described in connection with Fig. 3. The external channels have a section along the upper inclined portion of the blade where the wall 20 is not sufficiently close to confine the stream. However, the stream of fluid, after issuing from body 41, is carried along the upper inclined section of channel 18c by reason of its own momentum until it strikes wall 20, by which it is deflected downwardly through the lower portion of channel 18c in the same manner as described above.

It will be understood that in all forms of the bit described, the conventional well space

around the tool provides the path or channel taken by the outgoing fluid as it rises past the tool on its way to the ground surface, and that the channel for downcoming fluid is separated by parts of the tool and therefore distinct from the path taken by upwardly moving fluid.

Although I have shown the application of my invention to some typical drilling tools it will be understood that the invention may be applied to many other tools, and may be changed without departing from the spirit and scope of my invention; and it is to be understood that the foregoing description is to be considered as illustrative of rather than restrictive upon the scope of the invention described in the appended claims.

15

I claim as my invention:

1. A well drilling tool with cutting elements and an internal passage for circulation fluid, having an external fluid channel communicating at its upper end with the internal passage to receive fluid therefrom, said external channel being open to the tool exterior on one vertical side and at the lower end and so positioned on the tool in close proximity to the vertical well wall throughout substantially its entire length that the well wall at least partially closes the open vertical side of the channel to confine downwardly moving fluid therein, and a second external channel in which the fluid moves upwardly past the tool.

30

2. A well drilling tool with movable cutting elements mounted on a body and an internal passage for circulation fluid, having an external fluid channel in said body communicating with the internal passage to receive fluid therefrom, said external channel being open to the tool exterior on one side and so positioned on the tool body in close proximity to the well wall throughout substantially its entire length that the well wall at least partially closes the open side of the channel to confine fluid therein, and a second external channel in which the fluid moves upwardly past the tool.

35

3. A well drilling tool with a fixed cutting blade mounted on a body and an internal passage for circulation fluid, having an external fluid channel in said cutting blade communicating with the internal passage to receive fluid therefrom, said external channel being open to the tool exterior on one side and so positioned on the blade in close proximity to the well wall that the well wall at least partially closes the open side of the channel to confine fluid therein.

45

4. An earth boring tool comprising cutting elements, an internal passage for circulating fluid in said tool, a channel on at least one of said cutting elements having communication with said passage, said channel being open on one side at the tool exterior and being so positioned that when the tool is in a bore the walls of the bore will be in close proximity to the channel throughout substantially its entire length to close effectively the open side of the channel and guide fluid therein.
